Primary Examiner — George A Bugg*Assistant Examiner* — David Weir(57) **CLAIM**

The ornamental design for a foldable cart as shown and described.

DESCRIPTION

FIG. 1 is a top, front and left side perspective view of a foldable cart showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1; and,

FIG. 11 is an enlarged view of portion 11 in FIG. 1.

The broken lines in the drawings illustrate portions of the foldable cart that form no part of the claimed design. The dashed lines in FIG. 1, associated with detail areas '9', '10' and '11', define enlarged views shown in FIGS. 9, 10 and 11.
